CLAIM

I claim the ornamental design for a hanging shirt for display, as shown and described.

DESCRIPTION

FIG. 1 is a front view of a hanging shirt for display;
 FIG. 2 is a left side view of the hanging shirt for display;
 FIG. 3 is a right side view of the hanging shirt for display;
 FIG. 4 is a back view of the hanging shirt for display;
 FIG. 5 is a top view of the hanging shirt for display; and,
 FIG. 6 is a bottom view of the hanging shirt for display.
 The broken lines shown represent unclaimed subject matter and form no part of the claimed design.
